UNITED STATES PATENT OFFICE.

WALTER J. H. KING, OF ALAMEDA, CALIFORNIA, ASSIGNOR TO UNION LITHOGRAPH COMPANY, INC., OF SAN FRANCISCO, CALIFORNIA, A CORPORATION OF CALIFORNIA.

BINDER.

Application filed October 28, 1925. Serial No. 65,404.

This invention relates to binders and particularly to binders for loose leaves of books, such, for example, as check books and receipt books.

5 An object of the invention is the provision of a sectional binder, the sections of which may be readily and permanently interlocked.

10 Another object of my present invention is the provision of a binder capable of binding leaves together in such a manner that there is no possibility of any of the leaves being accidentally lost.

15 Another object of my invention is the provision of a sectional binder, one of the sections of which may be secured to a book cover by the manufacturer, while the other section may be readily applied by the person who inserts a filler in the book cover.

20 A still further object of my invention is the provision of a binder capable of withstanding comparatively high pressure without being damaged.

25 Another object of my invention is the provision of a binder free from outwardly extending projections so that the leaves held by the binder will not be damaged by being turned.

30 Another object of this invention is the provision of a binder which may be secured to a book cover in a manner permitting the top of the cover to be folded under the back of the cover, whereby the space occupied by the open book may be economized.

35 With the foregoing objects in view, together with such other objects as may subsequently appear, this invention resides in the construction and arrangement of parts hereinafter described and claimed, and illustrated in the accompanying drawings, in which

40 Figure 1 is a perspective view of an open book cover with a filler of loose leaves therein, bound together by two binders of my invention.

45 Figure 2 is a fragmentary vertical section of the binder, filler and cover shown in Figure 1, the book in this view being closed.

50 Figure 3 is a vertical section taken on the line 3—3 of Figure 2 in the direction of the arrows, shown in Figure 2, and

55 Figure 4 is a perspective view of the binder of my invention.

Referring to the drawings for more de-

tailed description thereof, it will be seen 55 that the binder is sectional, that it consists of an upper section 5 interlocked with an opposing lower section 6, both of which sections are preferably formed from comparatively broad metallic bands or ribbons. 60 The upper section 5 is given the form of an inverted **U** comprising an arcuate upper end portion 7 and vertical side portions 8. The side portions of the metal strip or ribbon from which the section 5 is formed, are bent inwardly and, from the points 9 around to the points 10, are pressed back into contact with the vertical side portions 8 and the upper arcuate portion 7. Below the points 9 and 10, however, the inwardly 70 bent side portions of the band from which the member 5 is formed, are spaced from the vertical portions 8, thus forming guide members 9^a and pockets 10^a between the guide members 9^a and the vertical portions 8. 75 The vertical portions 8 of the section 7 are punched to form projections 11 which slope inwardly and upwardly, and these projections have horizontal upper edges 12 broken away from the vertical portions 8 80 of the section 5.

85 The lower section 6 of the binder is **U**-shaped and comprises a bottom 13 and vertical sections 14 at right angles to the bottom 13. The vertical sections 14 are preferably resilient and are punched to provide apertures 15. The bottom 13 of the lower section 6 is provided with an aperture 17 through which extends a rivet 18 provided for the purpose of binding the lower section 90 to the back cover 19 of the book shown in Figure 1. Two of the sections 6 are riveted to the back cover of the book shown in Figure 1 and are spaced from each other.

95 A filler 21 which consists of checks 22 to the right of the scoring 23, and of stubs 24 to the left of the scoring 23, may be placed on the lower sections 6 before the upper sections 5 are made to engage the sections 6. The upper and lower stub portions 24 are 100 provided with apertures 25 through which one of the vertical portions 14 of each section 6 extends. The upper sections 5 may then each have one of their vertical portions 8 inserted into the apertures 25. The sections 5 may then be pressed down on the sections 6 so that the end portions of the verticals 14 enter the pockets 9^a. As the sections 5 are

pressed downwardly, the verticals 14, due to their resiliency, are snapped over the projections 11, which projections then extend through the apertures 15. The upper edges 5 of the apertures 15, which are preferably straight, lie above the edges 12, which edges prevent the sections 6 from being withdrawn from the sections 5. As previously stated, the turned-in side portions of the ribbon 10 from which the section 5 is formed, are pressed against the vertical portions 8 above the points 9, or, in other words, the pocket 9^a terminate at the points 9, so that the movements of the sections 5 and 6 toward 15 each other are thus limited.

It will thus be readily appreciated that when the sections 5 and 6 of my improved binder are snapped together, they are permanently interlocked.

20 From the foregoing description, it will be seen that I have provided a device which is capable of fulfilling the objects of my invention as hereinbefore stated.

Although I have shown and described one 25 embodiment of my invention, it is to be understood that the same is susceptible of various changes; and I reserve the right to employ such as may come within the scope of the appended claims.

30 I claim:

1. A ring for loose-leaf binders comprising

upper and lower substantially U-shaped mating members, forming a permanently closed loop or ring, one of said members having guideways for the reception of the 35 uprights of the other member, the uprights of one of said members having apertures and the uprights of the other members having projections adapted to be sprung into said apertures when said members are 40 brought together into interlocking position.

2. A device of the type described comprising a loose leaf binder consisting of two members adapted to telescope one within the other for forming a ring and cooperating 45 catches carried by said member for permanently securing them together.

3. In a binder, a U-shaped member having its curved edges bent back upon themselves for reinforcing the member, the backwardly 50 bent portion being spaced away from the walls of said member for a predetermined distance for providing guideways, a second U-shaped member having its ends receivable in said guideways, and means carried by 55 both of said members for permanently securing said members together, said first named member permitting leaves carried thereby to be swung over in the same manner as the movement of the leaves in a book.

WALTER J. H. KING.
